C. E. FROST.
THREAD GUIDE.
APPLICATION FILED AUG. 15, 1922.

Patented Dec. 12, 1922.

INVENTOR,
Charles E. Frost,
John Stewart,
ATTORNEY.

UNITED STATES PATENT OFFICE.

CHARLES E. FROST, OF PATERSON, NEW JERSEY.

THREAD GUIDE.

Application filed August 15, 1922. Serial No. 582,096.

To all whom it may concern:

Be it known that I, CHARLES E. FROST, a citizen of the United States, residing at Paterson, in the county of Passaic and State 5 of New Jersey, have invented certain new and useful Improvements in Thread Guides, of which the following is a specification.

A well known type of thread-guiding means for a number of threads being advanced lengthwise for any purpose, as in winding and the like, is a rail having a series of thread-guides, usually of porcelain, held seated upon it by springs alternating with the guides and consisting of elastic wires 10 each secured between its ends to the rail and having its ends bearing down upon and engaged in notches on the tops of two adjoining guides, each such guide having a central thread-guiding notch. When the 15 notch of any guide becomes unduly worn by the thread the guide has to be discarded, the guide not being adapted to be re-positioned in any way to present a fresh surface to the thread. Moreover this construction entails constant annoyance incident to the unshipping of the guides from the rail: if any spring end in any way slips off one 20 of the guides that guide will usually be thrown off the rail (which is usually reciprocated) and, if one guide is thus put out of commission, one or more of the others will follow because the unshipping of the 25 end of any spring reduces its tension and consequently its hold on the guide at its 30 other end. The holding of the guides in place is generally rendered all the more precarious because of the necessity of spacing the ends of the springs on any guide well apart so as to leave ample clearance 35 for the intervening thread.

The present invention contemplates a construction in which the guides may be turned to present fresh surfaces to the thread when they become worn and in which the guides, 40 though readily attachable to and removable from the rail or equivalent support, cannot become accidentally unshipped therefrom.

In the drawing,

Fig. 1 is a front elevation of a thread-guiding means embodying my invention;

Fig. 2 is a sectional view on line 2—2, Fig. 1; and

Fig. 3 illustrates one of the spring members in front elevation and plan.

55 *a* indicates the rail, in the present ex-

ample being a traverse rail adapted to be reciprocated longitudinally in any way on the roller bearings *b*. In its top surface this rail has a longitudinal groove *c*.

The guides are indicated at *d*, being in 60 the example illustrated spool-like members formed of any suitable material, as porcelain; as shown each has a central circumferential thread-guiding groove *e* and conical portions *f* on both sides thereof which 65 taper toward the same, the said portions presenting surfaces which slope toward the groove thus to encourage the return of the thread to the groove should it occasionally leave the same. Each guide is formed with 70 an axial bore *g* whose ends afford bearings for the means to secure the guide to the rail.

Said means consists of springs *h*. Each 75 spring is a wire having proper elasticity and formed with a central eye *h'* and with each extremity thereof bent first upwardly, as at *h''*, and then downwardly, as at *h'''*, at a slight angle. The springs are secured in the groove *c* by screws *i* extending 80 through their eyes *h'* and driven into the rail, all the springs being alined. Their adjoining ends stand quite close together.

Each spool-like guide *d* is attached to the rail, the springs being already in place, by 85 lifting the end of one spring and inserting it in the bore of the guide and then sliding the guide along until the end of the adjoining spring is cleared by the guide and can be then shifted into alinement with said bore, whereupon the guide is shifted back 90 into central relation to the two springs as shown in Fig. 1. Detachment of any guide from the rail is accomplished by a substantial reversal of these steps.

95 My construction obviously permits each guide to be turned on the springs as a pivot to present a fresh bearing surface to the thread when the guide groove *e* becomes worn. Further, while it is possible quite 100 readily to attach any guide to or detach it from the rail, it can not be accidentally unshipped therefrom. Even if the guide were shifted so far laterally that one spring would be disengaged it would still be effectively held by the other.

105 The seating stability of each guide on the rail is insured by the groove *c* on the sides of which the rounded periphery of the guide at its ends bears as shown in Fig. 2.

Having thus fully described my invention, what I claim and desire to secure by Letters Patent is:

1. In combination, a support, a thread-guiding member seated thereon and having opposite substantially central and aligned bearings, and spring means secured to the support and engaged with said member at its bearings, respectively, and coacting to hold said member seated on the support, said member being turnable on said means pivotally and having exterior means to guide the thread in any position to which it is turnable.
2. In combination, a support, a thread-guiding member seated thereon and having a substantially central bore therethrough, and spring means secured to the support and having ends extending into the opposite ends of the bore of said member and thereby coacting to hold the latter against its seat on the support, said member being turnable on said means pivotally and hav-

ing exterior means to guide the thread in any position to which it is turnable.

25

3. In combination, a support, a thread-guiding member seated thereon and having a substantially central bore therethrough and exterior means to guide the thread, and spring means secured to the support and having ends extending into the opposite ends of the bore of said member and thereby coacting to hold the latter against its seat on the support.

4. In combination, a grooved support, a thread guiding member having a substantially rounded periphery and seated on the support with its periphery in contact with the sides of the groove, and spring means holding said member seated on the support and being secured thereto, said member being turnable on said means pivotally and having exterior means to guide the thread in any position to which it is thus turned.

In testimony whereof I affix my signature.

CHARLES E. FROST.
